UNITED STATES PATENT OFFICE

163,220

LIGHTING FIXTURE GLOBE

Ralph Pryne, Pomona, Calif.

Application July 22, 1949, Serial No. 4,068

Term of patent 14 years

(Cl. D48—16)

To all whom it may concern:

Be it known that I, Ralph Pryne, a citizen of the United States, residing at Pomona, in the county of Los Angeles, State of California, have invented a new, original, and ornamental Design for Lighting Fixture Globe, of which the following is a specification, reference being had to the accompanying drawing, forming a part hereof, in which:

Figure 1 is a plan view of a lighting fixture globe showing my new design;

Figure 2 is a side elevational view thereof, and

Figure 3 is a cross sectional view to a smaller scale taken on the line 3—3 of Fig. 1.

The drawing is shaded to indicate contrasting appearance.

I claim:

The ornamental design for a lighting fixture globe, as shown and described.

RALPH PRYNE.
